UNITED STATES PATENT OFFICE.

EDWIN M. SAUNDERS, OF LOS ANGELES, CALIFORNIA.

PLASTER-BANDAGE ROLLER.

1,241,029.

Specification of Letters Patent. Patented Sept. 25, 1917.

Application filed April 18, 1916. Serial No. 91,911.

To all whom it may concern:

Be it known that I, EDWIN M. SAUNDERS, a citizen of the United States, residing at Los Angeles, in the county of Los Angeles 5 and State of California, have invented certain new and useful Improvements in Plaster-Bandage Rollers; and I do hereby declare the following to be a full, clear, and exact description of the invention, such as 10 will enable others skilled in the art to which it appertains to make and use the same.

This invention relates to new and useful improvements in plaster bandage rollers and the principal object of the invention is to 15 provide a device for distributing plaster of Paris over bandages and rolling the same into convenient form.

Another object of the invention is to provide a device which will roll bandages of 20 various widths and distribute the plaster of Paris in various thicknesses so as to suit the requirements of the user.

A further object of the invention is to provide a distributor which may be thrown 25 into operative or inoperative position so as to leave the table clear for the proper positioning of bandages thereon.

A still further object of the invention is to provide a device which will prevent the 30 bandages from being torn or otherwise injured when they come in contact with any foreign object which might have fallen into the plaster of Paris.

With these and other objects in view, the 35 invention consists in the novel combination and arrangement of parts which will be fully set forth in the following specification and accompanying drawings, in which:—

Figure 1 is a top plan view of a bandage 40 roller constructed in accordance with this invention.

Fig. 2 is a side view in elevation of Fig. 1.

Fig. 3 is a longitudinal sectional view 45 through the device, and

Fig. 4 is a transverse sectional view taken on the line 4—4 of Fig. 2.

Referring to the drawings the numeral 1 designates the table or bed of the device which is supported on suitable legs 2 arranged at opposite corners. A suitable bin 50 designated generally by the numeral 3 is supported beneath the table or bed 1 and is adapted to receive the plaster of Paris which is to be spread on the bandages. A reserve receptacle 4 is positioned on the table 1 at one end and communicates through an open-

ing 5 in said table with the bin as clearly shown in Fig. 3. Secured to the end of the table opposite the reserve receptacle 4 is a suitable receptacle 6 for containing the 60 bandages which are to be treated. A suitable wall 7 is secured to the rear side of the table and secured centrally thereof and extending from the bottom of the bin to a point in a plane above the upper edge of 65 the wall is the elevator shaft 8 the lower portion of which opens into the bin in the manner illustrated in the drawings.

Journalized within the elevator shaft near its upper and lower terminals are the rollers 70 9 over which the elevator belt 10 passes on which the buckets 11 are carried. As illustrated in the drawing it will be seen that the inner run of the elevator belt 10 passes upwardly while the outer run travels downwardly thus rotating the rollers 9 in a clockwise direction. The upper roller 9 is mounted on a shaft the end of which is extended as at 12 and carries the pulley 13 by means of which the elevator is controlled. 80

The drive wheel 14 is mounted on a shaft 15' which extends through the elevator between the runs of the belt 10 and beneath the table 1 to the forward side thereof where it is provided with a crank 15^a for manual rotation of the device. The opposite end of this shaft carries the drive wheel 14 and a suitable pulley 16 and the belt 15 runs over the drive wheel and over the pulley 13 so that upon rotation of the drive wheel the 90 elevator will be actuated. A suitable belt 17 passes over the pulley 16 and over a suitable pulley 18 mounted on the end of the shaft 19 which is journaled in suitable brackets 20 near the bottom of the bin. This 95 shaft carries a suitable bevel pinion 21 which meshes with the bevel pinion 22 mounted on the shaft 23 which is journaled within the bin and carries a worm 24 for agitating the plaster of Paris and feeding 100 the same toward the elevator.

The upper end of the elevator communicates with a suitable chute 25. The lower terminal of the chute 25 is positioned near the center of the table 1 and in a plane 105 slightly above the upper side thereof and is adapted to direct plaster Paris dumped into the chute downwardly and onto the bandage at the lower end thereof. In this way it will be seen that the plaster Paris will be deposited on the bandage passing through the device. In order to draw the bandage 110

through the machine a suitable spindle 26 is provided and carries at one end a friction wheel 27, which is adapted to run against the wheel 14 so that the spindle is frictionally rotated by the rotation of the wheel 14. The spindle is journaled as at 28 in suitable blocks 32 slidably mounted in frames 29 secured on the opposite sides 7 of the table 1. The frames 29 carry set screws 30, which are provided with springs 31 bearing against the blocks 32, whereby the spindle 26 is held under a tension and the friction wheel 27 keyed on the end of the spindle 26 is held in engagement with the wheel 27. It will thus be seen that the tension on the wheel may be adjusted to suit varying conditions.

In order to hold the bandage flat and in proper place on the table a suitable roller 33 is provided, which is mounted on a suitable pivoted arm 34, which in turn is adapted to be swung downwardly in the position shown in Figs. 1 and 3 so as to engage the bandage prior to its passage beneath the lower end of the chute 25. It will thus be seen that the weight of the roller will hold the bandage flat. The distributor is designated generally by the numeral 35 and comprises a triangular piece 36, which is pivoted to an arm 37 similar to the arm 34 and is adapted to be swung downwardly to the position shown in Figs. 1 and 3, or upwardly to the position shown in Figs. 2 and 4. The slots 36^a which are positioned on each side of the shoe receive the excess plaster Paris from the shoe, so that the excess plaster Paris is returned to the bin 3. It will also be seen that the pressure of the shoe 36 on the bandage may be regulated so that the thickness of the plaster Paris spread on said bandage may also be regulated.

While in the foregoing there has been shown and described the preferred embodiment of this invention, it is to be understood that such changes may be made in the combination and arrangement of parts as will fall within the spirit and scope of the appended claims.

What is claimed is:

50. 1. In a device of the class described including a table, a spindle mounted above the table and adapted to wind bandages, means to convey plaster Paris to the bandage in front of said bandage receiving means, said table having a series of longitudinal slots positioned on each side of the bandage, and means positioned in rear of said conveyer

and between said slots to scrape any excess plaster Paris off of said bandage toward said slots, as and for the purpose specified. 60

2. In a device of the class described including a table, having a series of spaced longitudinal slots, a spindle rotatably mounted above the table adapted to wind bandages and guide the same between the slots, means to convey plaster Paris to the bandage in front of said bandage receiving means, a scraper positioned in front of said bandage receiving means and centrally of said slots, said scraper having its front wall inclined rearwardly from the central portion thereof toward said slots, whereby any excess plaster Paris is scraped off said bandage toward said slots, as and for the purpose specified. 75

3. A device of the class described including a table having slots therein, a bin positioned beneath the table, a spindle rotatably mounted above the table, an elevator at one side of the table and operable within the bin, a chute connected to the upper end of the elevator, the lower end of the chute being disposed immediately above a bandage which is to be wound, a roller for holding said bandage flat when passing beneath the chute and a distributor immediately in the rear of the chute adapted to spread a material over the face of the bandage and scrape any excess of material off to the side and through the slots in the table back into the bin, the said roller and distributor being pivoted at one of their ends to said table, whereby they can be swung upwardly and out of engagement with the table to permit the device to be readily adjusted for operation. 90

4. In a device of the class described, a table, a spindle rotatably mounted about the table and adapted to wind bandages, a guide roller pivoted to the table and adapted to be swung downwardly to hold the bandage which is being wound flat on the table, means for conveying plaster Paris to the bandage immediately in rear of the roller, a distributor adapted to spread the plaster Paris over the bandage and means carried by the bandage receiving spindle to control the speed of rotation of said spindle. 100

In testimony whereof I affix my signature in presence of two witnesses.

EDWIN M. SAUNDERS.
